DRAFT RIGGING

Donald S. Barrows, Rochester, N. Y., assignor to
The Symington Company, New York, N. Y., a
corporation of Maryland

Application February 18, 1928, Serial No. 255,466

8 Claims. (Cl. 213—69)

This invention relates to draft rigging for railway rolling stock and more particularly to connecting means between the coupler and yoke thereof whereby a desired amount of angling therebetween is permitted.

The principal object of my invention, generally stated, is the provision of a key-connected coupler and yoke with the key serving to transmit draft forces therebetween and a shim seated on said key and formed to permit pivotal motion between said coupler and key, an auxiliary member or swivel block being provided between the butt of the coupler and associated cushioning mechanism for permitting similar pivotal motion therebetween, said swivel block being operatively connected to the coupler, preferably by means aiding or not interfering with the pivotal motion thereof.

An object of my invention is to provide a swiveling or pivotal connection between the coupler and yoke members in railway draft rigging in which a shim seated on a key connecting the coupler and yoke serves as a pivoting member instead of a pin extending entirely through the

Another object of my invention is to provide a pivotal connection between the coupler and yoke members in railway draft rigging in which a key serves to transmit draft forces between the coupler and yoke and a swivel block is provided formed with a forwardly opening pocket in which is seated the coupler butt, the coupler and block being formed with interengaging faces for transmitting buffing forces from the coupler to the cushioning mechanism without detriment to said block, said faces being adapted to permit pivotal motion between the coupler and block members, and means being provided between the coupler and swivel block for operatively connecting said members without interfering with said pivotal motion.

A further object of my invention is to provide a swivel block connected to the end of the coupler and forming in effect a coupler with an articulated butt, the rear face of said block being adapted to engage cushioning mechanism, and the front face being pocketed and curved for embracing the rear end of the coupler, means extending between the upper and lower portions of said coupler and swivel block for operatively connecting the same while permitting pivotal motion therebetween.

A still further object of my invention is to provide a pivotal connection between a preferably horizontal yoke and coupler, said yoke being pro-

vided with slots in the forward portions of the arms thereof with a key extending through said slots and corresponding slots in the coupler for operatively connecting said yoke and coupler and transmitting draft forces therebetween, a 60 shim member being seated on said key and in a pocket of the coupler for permitting pivotal motion between the key and coupler, and another member between the coupler butt and the cushioning means for transmitting buffing forces 65 therebetween, said member having bearing faces for permitting pivotal motion between it and the coupler, and trunnion means operatively connecting said member and coupler butt without interfering with the pivotal motion between the 70 parts.

Other objects and advantages of the invention relating to the particular arrangement and construction of the various parts will become apparent as the description proceeds.

Referring to the drawings illustrating my invention, the scope whereof is defined by the appended claims:

Figure 1 is a plan view of a coupler and yoke connected in accordance with one embodiment of 80 my invention.

Figure 2 is a vertical longitudinal sectional view on the line 2—2 of Figure 1, looking in the direction of the arrows.

Figure 3 is a horizontal sectional view on the 85 line 3—3 of Figure 2, looking in the direction of the arrows.

Figure 4 is a vertical longitudinal sectional view corresponding to Figure 2 but showing a modification.

Figure 5 is a plan view of a coupler and associated swivel block corresponding to Figure 1 but showing another modification.

Referring to the drawings in detail, like parts being designated by like reference characters, and first considering the embodiment of my invention illustrated in Figures 1, 2 and 3, I have shown a coupler 1 connected to a yoke 2 by means of a key 3. Although a horizontal yoke is illustrated, I do not wish to be limited to such showing which is merely illustrative. The forwardly extending arms 4 of the yoke 2 are slotted, as indicated at 5 and 6, respectively, for the passage of a key 3 therethrough and extend on each side of the coupler 1. The coupler is provided with a slot 7 through which passes the key 3. The rearward portion of the slot 7 is enlarged to form a pocket 8, said pocket being provided with rear faces formed as cylindrical bearing portions 9, 10 and 11. It will be noted that the slotted portion 7 110

closely embraces the key 3 with only normal clearance therebetween whereby said key is properly supported in substantially horizontal position.

A shim 12 shaped to accurately fit into the rear portion of the pocket 8 and formed with correspondingly curved bearing portions 13, 14 and 15 for pivotal engagement with respect to the coupler bearing portions 9, 10 and 11, respectively, is provided and seated in said coupler pocket, as illustrated most clearly in Figures 2 and 3. The forward face 16 of the shim 12 when positioned in the coupler pocket is normally vertical and substantially flat except where a bearing pocket 17 is provided for engagement with the key member 3. It will be noted that it is necessary to first insert the shim 12 in place in the pocket 8 of the coupler and then the key 3 is passed through the slot 7 therein which serves to lock the shim in place and prevent loss thereof while the parts are assembled.

The rear face or butt portion 18 of the coupler is curved co-axially with respect to the curved portions 9, 10 and 11 of the pocket 8 therein. This curved outer portion on the coupler fits into and engages with a separable swivel block or auxiliary member 19 normally disposed between the coupler 1 and the draft gear or cushioning mechanism 20, illustrated diagrammatically by dot and dash lines. The member 19 is provided with a co-axially curved bearing portion 21 formed as a pocket into which the butt of the coupler fits and bears against.

The auxiliary member or swivel block 19 is provided with forwardly extending arms 22 and 23, both arms being provided with receptacles, apertured or pocketed, as indicated at 24 and 25, to provide bearings for engaging trunnions 26 and 27 on the top and bottom, respectively, of the coupler 1. These arms 22 and 23 may initially be flaring away from each other, as indicated by dot and dash lines in Figure 2, and finally bent toward each other into engaging relationship with the top and bottom faces of the coupler where the trunnions 26 and 27 engage respectively in the apertures 24 and 25 of said arms whereby said coupler and swivel block are operatively connected to facilitate or at least not interfere with the pivotal motion therebetween about the curved bearing faces 18 and 21.

To facilitate engagement between the trunnions 26 and 27 and the arms 22 and 23 on the swivel block, said trunnions are preferably slightly tapered to a decreased cross-section outwardly or away from the parts on which they are formed, as illustrated, or formed approximately frustroconical and the apertures in the arms of the swivel block correspondingly formed, said tapering, however, being only necessary longitudinally on account of the manner of application of the swivel block.

To consider the theory underlying the connection between the swivel block and the top and bottom faces of the coupler by means of trunnions which are necessarily co-axial with the bearing faces between the butt of the coupler and the engaging curved surface of the swivel block, it should be observed that the mechanical performance of a segmental annular shim depends on its being forced to observe its theoretical center. If, on the other hand, there were no trunnion connection between the swivel block and the coupler butt, upon pivotal motion between said members, there would be a tendency of the parts to cant with respect to each other, thereby increasing the friction therebetween and impairing the efficiency of

the pivotal connection. A wheel rotates smoothly because it has a fixed center of relatively small diameter on which to turn. If the disk of a wheel were held against rotation and the tire were required to rotate on the disk the frictional resistance would be multiplied many times. If, instead of a complete tire we have only a small segment, we then have a shim such as the swivel block illustrated, and in order to improve the mechanical performance of the associated parts and prevent sticking, the trunnion connection disclosed is provided which, in addition, functions to maintain an operative relation between the coupler and swivel block and cause said members to travel forwardly and rearwardly as a unit.

Referring now to the embodiment of my invention illustrated in Figure 4, a construction is there disclosed comprising the coupler 1^a, a yoke 2^a, and a connecting key 3^a extending therebetween. Said yoke and key may be identical with those of the first embodiment and the coupler may be nearly identical with that of the first embodiment, having a shim 12^a with co-axially curved bearing surfaces engaging correspondingly curved surfaces on the coupler and a front face notched to engage the rear edge of the key, as in the first embodiment. The rear end or butt portion 18^a of the coupler is likewise co-axially curved with respect to the curved portions on the inner surface thereof and a cooperative swivel block 19^a is provided as in the first embodiment. The forwardly extending arms 22^a and 23^a of said swivel block, however, instead of being apertured for engaging trunnions on the coupler butt, are provided with inwardly or respectively downwardly and upwardly extending trunnion portions 26^a and 27^a which, after the arms 22^a and 23^a are bent to position as in the first embodiment, seat themselves in correspondingly-shaped pockets 24^a and 25^a. The shape of said trunnion portions and corresponding trunnion receiving pockets preferably corresponds with that of the first embodiment. Except as specifically disclosed, the present embodiment preferably corresponds substantially with that of the first embodiment.

Referring now to the embodiment of my invention illustrated in Figure 5, a construction is there disclosed which is preferably identical with that of the first embodiment except that the connection between the coupler 1^b and the swivel block 19^b involves forwardly extending arms 22^b on the swivel block which, instead of being apertured as in the first embodiment, are slotted to the ends, as indicated at 24^b, so that said swivel block need not be applied to the coupler by bending said arms to position but said arms may be arranged in normally parallel relation and the swivel block slipped into place on the butt of the coupler and then retained thereon by cotter 135 or other connecting means 28 passing through registering apertures 29 in the bifurcated ends of the arms 22^b. On account of the avoidance of bending the arms 22^b, the trunnions 26^b on the yoke may be cylindrical rather than tapered and the notches or slots 24^b correspondingly formed. Inasmuch as the only stress applied on the retaining members or cotters 28 is that necessary to keep the parts in assembly while in the storehouse or before application to the car, no very great strength is required thereof. Otherwise the construction of the parts and arrangement thereof may be identical with that of the first embodiment.

It will be apparent that by virtue of the afore-

described construction a strong and readily manufactured connection between the coupler and yoke members in railway draft rigging is provided as the interior shim permits pivotal motion between the coupler and the key member in a substantially horizontal plane by virtue of the engaging cylindrical bearing faces on said shim and coupler. A slight amount of vertical angling may also be permitted due to the clearance between the key and the slotted portions of the coupler and yoke.

When draft forces are applied to the coupler such forces are transmitted first to the shim 12, then to the key 3, and through said key to the forwardly extending arms of the yoke. When buffing forces, however, are applied to the coupler the key is relieved of substantially all strains because such buffing forces are transmitted to the swivel block or auxiliary member 19 and from there to the engaging cushioning mechanism, the key moving rearwardly with the coupler in the elongated slots 5 and 6 of the yoke. By reason of the pivotal relation between the coupler butt and swivel block a flat and substantially transverse face is always presented to the cushioning mechanism for the efficient transference of buffing forces thereto.

Having now described my invention, what I claim is:

30 1. In railway draft rigging, a coupler formed with a slotted butt, a yoke, a key extending through the slotted portions in the coupler butt and corresponding slots in the yoke for operatively connecting said parts, a shim enclosed in the butt, engaging the rear edge of the key, and pivotally movable with respect to said butt, an external shim embracing the butt of the coupler and separable therefrom, and trunnions for connecting the external shim and butt together for pivotal motion therebetween, formed on the top and bottom of one of said members and received in pockets in the other, said trunnions decreasing in diameter away from the member on which they are formed.

45 2. In railway draft rigging, a slotted coupler, a slotted yoke, a key passing through said slots for operatively connecting said coupler and yoke, a shim seated in said coupler and both shim and coupler provided with correspondingly curved cooperating bearing faces permitting pivotal motion therebetween, said shim also engaging the key and both provided with corresponding bearing faces, a swivel block embracing the butt of said coupler, and approximately frustro-conical trunnion means received in corresponding pockets and extending between said block and coupler for operatively connecting the members while permitting pivotal motion therebetween, the larger bases of said trunnion means being at the member from which they extend.

55 3. In railway draft rigging, a slotted coupler having a curved butt portion, a slotted yoke, a key passing through said slots and connecting said coupler and yoke, a swivel block with a bearing pocket curved to correspond with the butt portion of the coupler, bendable arms embracing the butt portion of said coupler, and trunnion means extending between said arms and the adjacent faces on the coupler for operatively connecting the parts while permitting pivotal motion therebetween, said trunnion means being tapered to a decreased diameter away from the parts on which they are formed to facilitate assembly.

75 4. A coupler provided with a butt portion, an

associated swivel block, the rear wall of said butt portion being curved as a cylindrical bearing for pivotal motion with respect to said swivel block and formed with a pocket therein, the inner face of said pocket being co-axially curved with respect to the rear wall for engagement with a correspondingly curved shim and slotted for receiving a connecting key, the upper and lower faces of said butt and the associated portions of the swivel block being formed with means for connecting said coupler and block while permitting pivotal motion therebetween, said means comprising trunnions formed on one of said parts, decreasing in size as they extend therefrom, and disposed in corresponding receptacles in the other.

80

5. A coupler for railway draft rigging comprising a shank and a separable butt end section, said butt end section and shank having complementary curved pressure-transmitting surfaces, said butt end section having upper and lower flanges respectively overlying the top and bottom surfaces of said shank, and trunnions integral with one of said members tapered to a decreased cross-section away from said member, and received in corresponding pockets in the other for pivotally mounting said butt end section on said shank.

6. In combination, a coupler for railway draft rigging comprising a shank with a slot and a butt end section separable from said shank, said butt end section and shank having complementary curved pressure-transmitting surfaces, said shank having upper and lower flanges respectively overlying the top and bottom surfaces of said shank, and trunnions integral with one of said members and disposed in corresponding receptacles in the other for pivotally mounting said butt end section on said shank, said trunnions being tapered to decreased cross-sections as they extend from the member on which they are formed into the pockets of the other, a key passing through the slot in said shank for connecting the coupler to associated draft rigging, and means to permit relative swiveling of the coupler with respect to said key on draft, held in place by said key, disposed between the rear edge of the latter and said shank, formed with a rear curved surface engaging a complementary curved surface on the shank, and a front notched portion receiving the rear edge portion of said key.

7. A butt member separable from and adapted to cooperate with the shank of an associated coupler and comprising a normally upright force-transmitting portion having a generally flat rear face and a concave forward face adapted to engage a cooperating rear face of the shank, said upright portion being provided with forwardly extending arms carrying means involving portions tapered to a decreased cross-section as they extend away from the inner faces of said arms for pivotally connecting said butt member and shank.

8. In a coupler attachment, the combination of a coupler shank and a yoke having horizontal aligned slots; a connecting key seating in said slots; a draft gear in said yoke, and independent draft and buff equalizing members, one of said members seated within said shank and bearing upon said key, and the other of said members being interposed between said shank and gear, said last named equalizing member having bendable portions separable from, overlying and underlying the rear portion of said shank, and pivotally connected to the latter by trunnions on one received in bearings in the other.
